(57) **CLAIM**

The ornamental design for a “protective cover for an electronic communication device,” as shown and described.

DESCRIPTION

FIG. 1 is a front perspective view of a protective cover for an electronic communication device showing our new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a rear perspective view thereof;

FIG. 9 is a front perspective view thereof, showing the round feature on the interior rear in a recessed configuration;

FIG. 10 is a rear perspective view thereof, showing the rectangular feature on the exterior rear in a protruding configuration;

FIG. 11 is a front perspective view thereof, shown in a state of use with an environmental electronic communication device; and,

FIG. 12 is a rear perspective view thereof, shown in a state of use with an environmental rear accessory.

The broken lines in FIGS. 11 and 12 depict an environmental electronic communication device and an environmental rear accessory that form no part of the claimed design. All other broken lines throughout the drawing figures depict portions of the protective cover that form no part of the claimed design.
